UNITED STATES PATENT OFFICE.

HELLMUTH LANGER AND GEORG BOCK, OF STEGLITZ, NEAR BERLIN,
GERMANY.

TOOL-HOLDER.

SPECIFICATION forming part of Letters Patent No. 779,289, dated January 3, 1905.

Application filed September 19, 1902. Serial No. 124,038.

To all whom it may concern:

Be it known that we, HELLMUTH LANGER and GEORG BOCK, subjects of the German Emperor, and residents of Steglitz, near Berlin, 5 in the Empire of Germany, have invented a new and Improved Tool-Holder, of which the following is a full, clear, and exact description.

Our invention relates to a new tool-holder especially adapted to be used in connection 10 with lathes.

An essential feature of the invention consists in the special construction of the locking device, another feature of the invention being the arrangement of the cutting-tool.

15 The various features of this invention will be hereinafter described, and pointed out in the claims.

In the accompanying drawings, Figure 1 is a side elevation of the tool-holder with the 20 tool. Fig. 2 is an end view of the tool-holder. Fig. 3 is a plan view of the tool-holder corresponding to Fig. 1. Fig. 4 shows a longitudinal section of the tool. Fig. 5 shows the locking device. Fig. 6 is a longitudinal section of a modification of the tool-holder.

The tool-holder consists of a body portion α , which is rectangular in cross-section or has 25 four flat sides, (indicated by 1, 2, 3 and 4 in Fig. 2.) At the forward end the body portion is made substantially conical or tapered from the sides 3 and 4 toward the corner formed by the junction of the sides 1 and 2. The body is provided with a tool-receiving 30 hole α' , which is arranged at a downward or acute angle with relation to the top and bottom sides of the body and also at an acute angle transversely of the body or with relation 35 to the edge ff' . This opening for the tool c passes out through the apex of the conical formation or at the corner 1 2. The body is provided with a longitudinal bore α'' in which is arranged a locking-rod b . This bore is arranged at an angle with relation to the body and communicates with the hole α' . 40 The rod b is tapered at its end engaging with the tool c , and it is prevented from rotary movement by means of a pin g extended from the body into a channel b^2 , formed in said rod. The tapered portion of said rod is indicated 45

at b' . At the rear end the rod b has rotary connection with a screw-block d . As here shown, the end of the rod b is provided with a ball k , seated in a socket l , which passes into a recess α^3 in the body portion, and as a means for holding the ball in said socket member the end wall m of the socket member may be crimped down upon the ball, as clearly indicated in Fig. 4. By this construction the rod is moved both inward and outward by the turning of the screw-block. 60

A block d has a threaded portion n for engaging with the interior thread α^3 of the body, and rearward of this threaded portion is an enlarged chamber α^4 for receiving an enlarged cylindrical portion o of the screw. By this 65 construction dust or dirt will be prevented from reaching the screw-threads.

In Fig. 6 we have shown the rod b as connected to a screw d by means of a pin s , having a head t , which engages against the outer 70 end of said screw. The inner end u of this rod b is made conical in form, so that it will operate against the tool c , even if it should be turned with the rotary movement of the adjusting-screw. 75

Having thus described our invention, we claim as new and desire to secure by Letters Patent—

1. A tool-holder comprising a bar having a tool-opening and a thrust-pin opening, the tool-opening extending from near one side at the front of the bar obliquely toward the rear of the bar, a thrust-pin in said thrust-pin opening, a screw for actuating said thrust-pin, and a swivel connection between the screw and 80 the thrust-pin. 85

2. A tool-holder comprising a bar having a tool-opening and a thrust-pin opening, the tool-opening extending from near one side at the front of the bar obliquely toward the rear of the bar, a thrust-pin arranged in said thrust-pin opening having a reduced extension, a sleeved screw arranged on said reduced extension, and means for securing said extension in said screw for forming a swivel therewith. 90 95

3. A tool-holder comprising a body or shank having a cutter-receiving opening at an acute angle to its longitudinal axis and a

cutter therein, and having a longitudinal bore intersecting the cutter-receiving opening adjacent that end from which the cutting edge of the cutter projects and inclined to the axis 5 of the shank, said bore being also inclined to the axis of the cutter-receiving opening at a lesser angle than that formed by the axes of the shank and cutter-receiving opening, in combination with a rod in said bore, arranged 10 to have one end bear upon the side of the cutter, and means to force the rod endwise, substantially as described.

4. A tool-holder comprising the holding-bar with a tool-opening therein, and a thrust-pin opening arranged on a sufficient slant to 15 the tool-opening to effect a binding action,

of a thrust-pin arranged in the thru opening and acting upon a tool in the tool-opening, a thrust-pin arranged in said thrust-pin opening, said pin having a beveled end to 20 contact a tool in the tool-opening, a screw for actuating the thrust-pin in both directions, and a swivel connection between the screw and thrust-pin.

In witness whereof we have hereunto signed 25 our names, this 8th day of September, 1902, in the presence of two subscribing witnesses.

HELLMUTH LANGER,
GEORG BOCK.
